ABSTRACT OF THE DISCLOSURE

Station signaling with speech immunity and noise exclusion are achieved in a system that can use a speech-immune VF receiver and a standard VF receiver both online at the same time at the receive end. The station circuit alternately presents pulsed-DC key signals and code-pair VF signals. The speech-immune receiver can accept the VF signals while ignoring the pulsed DC; the standard receiver can receive the VF signals if activated by a tuned VF receiver responsive to the pulsed DC.

The invention relates to voice-frequency key dialling and particularly to the transmission of dial information items from a subscriber station to an exchange.

A number of voice-frequency key dialling methods are known which can be divided into two groups. The main problem of all these methods is to provide for so-called speech immunity, i.e. provide measures to assure that no signals are accurately imitated by the voice frequencies. Based on the measures selected, the methods can be subdivided into two groups. The first group of methods provides a signal code at the voice frequencies having characteristics which distinguish it from speech within the voice-frequency band and which can be evaluated via speech immune voice-frequency receivers. In the second group of methods a key-signal, preferably a D. C. signal, is added to each code signal through which signal standard voice-frequency receivers can be set ready for operation.

When weighing the foregoing two groups of methods against each other the methods employing the voice-frequency safe signal code and speech-immunity voice frequency receivers are preferred where a high signalling speed is desired and where lines are inserted into the transmission path, terminating on either end by transformers or capacitors, which cannot transmit D. C. key signals without extra facilities. The disadvantage of these methods is that the receiving devices are more expensive, and in the presence of noise-interference on the line, they can be blocked to signalling.

The second group of methods employs standard voice frequency receivers and so-called key signals and do not reach a high signalling speed, because, prior to evaluation of the voice frequency code signal, the key signal must be evaluated and the standard voice frequency receiver connected thereupon. Moreover, as already indicated, the use of key signals ordinarily requires the addition of means for transmitting DC signals at lines terminating on either end by transformers or capacitors. The big advantage of these methods is, however, that an absolute safety against interfering speech can be obtained and no troubles are to be feared, even if using the methods on lines susceptible to interfering noise.

It is an object of the invention to provide a voice frequency key dialling system according to the method which provides at a transmission station for the operation of either speech immunity voice frequency receivers or the operation of standard voice frequency receivers (which

2

cannot distinguish transmitted tone from similar voice signals) which are connected for the key signal via the receiver on the receiving end. It is thus an object to combine advantages of both groups of methods into operating systems.

The voice-frequency key dialling method, particularly for the transmission of dial information items between subscriber stations and the exchange system is characterized, according to the invention, in that the code signals are formed by a pulsed-DC key-signal (e.g. a loop interruption for a short time) and a speech-immunity signal frequency combination (e.g. tones taken two-at-a-time). Evaluation of the combined signal may be performed either by speech immunity voice frequency receivers which ignore the key signal, or by standard voice-frequency receivers which are switched ready-for-operation by said key signal. The selection and use of one or the other receiving facility can be made depending upon the conditions expected to prevail. Thus, for any given receiver safe and optimum transmission of information can be assured by use of the appropriate one of the alternative receiver systems.

A particularly advantageous embodiment of the invention is characterized in this that, on the receiving end, when using standard voice-frequency receivers, the key signal is marked by balancing amplitudes formed by short-time interruptions of the DC signals, e.g. occurring at a line interruption, and that said balancing amplitudes are received by a suitably designed and inductively connected voice frequency receiver. In such a case the key signal can be transmitted via lines, terminating on either end by transformers or capacitors. The short-time loop interruption or loop current reduction is produced, according to the invention, by the switch-over of a contact, particularly a ball-type armature contact with separate break- and make-contact. The speech-immunity signal frequency combinations of the code signals are formed in the two-group code 2 x 1-out-of-4 (formed by two tones each taken from a group of four tones), according to a particularly advantageous design.

The invention is now in detail explained with the aid of the accompanying drawing which shows, in principle, the method and both receiving facilities usable therewith.

The part of the drawing to the left of the dash-dot line 2 shows the transmitting end, i.e. the subscriber station of a telephone exchange, schematically. The station circuit S_t is connected, after the handset has been lifted, with the power unit S_p of the exchange via the line L , from which unit the station receives the feeding current. For transmitting dial information items the keys T of the dialling key set are actuated in compliance with the telephone number of the subscriber called. As indicated at the transmitter T_{onG} via a key contact T the corresponding voice-frequency code signal is set. Using a two-group code 2 x 1-out-of-4, a two-frequency generator is provided which furnishes, after actuation of the key, the associated code signal. At each pressing of the key the switch-over contact u is actuated, too, whereby the station S_t is switched off and the transmitter T_{onG} switched on. It is thereby assured, that, during the emission of a voice-frequency code signal, speech frequencies produced by the microphone of the station S_t cannot influence the signalling. The switch-over period of the contact u precedes, as so-called key signal, the voice frequency code signal. This switch-over period can be made independent of the duration of pressing the key and independent of the speed with which the keys are actuated. An armature contact may be provided having a separate break- and make-contact and being controlled by a permanent magnet, mounted to a mechanical coupling element. During the switch-over period of contact u the loop current is interrupted or reduced.

These composed code signals can now be evaluated in two different ways.

The right portion of the drawing schematically shows both possibilities; however, it is expected that only one of the illustrated receivers will usually be connected to the line at any given location and any given time, though both might be used, of course, if desired. The top part shows on the receiving end, besides the unit S_p , a speech-immune voice frequency receiver $TonE1$, connected to the line. The type of connection makes no difference for this receiving facility, because the voice-frequency portion of the code signal is immune against speech, and the key signal, accompanying the code signal, can be neglected when evaluating said code signal. The transmission path can be left in an arbitrary manner via lines, terminating on 15 either end by transformers or capacitors, and also via other routes.

The lower part shows the second receiving facility. Since only standard voice frequency receivers $TonE2$ are used the speech immunity must be obtained via the key signal. To this end a receiver SE is provided for the key signal which is switched on only when the standard voice frequency receiver $TonE2$ responds. The receiver SE can be designed in an arbitrary manner, in order to evaluate the loop interruption or the loop current reduction. Most of the methods known use suitable direct current evaluators which supervise the potentials on the line wires. A particularly advantageous arrangement is obtained, if the balancing amplitudes, occurring at a defined, constant line interruption, and the there-to connected receiving facility are evaluated. Then a correspondingly tuned voice frequency receiver SE is inductively connected with the line, as indicated schematically by the transformer U_e . The capacitor C performs the required disconnection of direct current.

What is claimed is:

1. A voice-frequency key dialling system for the transmission of dial information between a calling subscriber station and exchange where the exchange includes as components a choice between a speech immune voice-frequency receiver, and a standard voice frequency receiver coupled with a tuned voice frequency receiver, said system comprising:

a power unit,
a calling subscriber station including a station circuit and a tone generator,
a line having transmit and receive ends,

means for alternately connecting said station circuit and said tone generator to the transmit end of said line to alternately transmit pulsed-D.C. key-signals and coded voice frequency signal combinations over said line,
means connecting said power unit to said receive end of said line,
the receive end of said line including as components a choice between a speech-immune voice frequency receiver and a standard voice frequency receiver coupled with a tuned voice frequency receiver, where a speech immune voice frequency receiver will respond to said signal frequency combination and a tuned voice frequency receiver will respond to the balancing amplitudes of the pulsed-D.C. key signals and switch "on" said standard voice frequency receiver.

2. A voice frequency key dialling system as claimed in claim 1 in which said tone generator includes means for generating frequency combinations formed as tones taken two-at-a-time from two groups of four tones.

3. A voice frequency key dialling system as claimed in claim 1, in which the standard voice frequency receiver at the receive end of said line senses the key signal for balancing amplitudes occurring at a line interruption.

4. A voice frequency key dialling system as claimed in claim 3, in which any tuned voice frequency receiver is inductively coupled to receive the key signal.

5. A voice frequency key dialling system as claimed in claim 1, in which the means for transmitting a key signal includes means for generating a loop current reduction to form said key signal.

6. A voice frequency key dialling system as claimed in claim 5, in which the means for generating the loop current reduction includes means for making and breaking contact through said line to said power unit.
